UNITED STATES PATENT OFFICE.

CHARLES ASHTON HENRY BULLOCK, OF LONDON, ENGLAND.

PRINTING PRESS.

Application filed September 5, 1922. Serial No. 586,250.

To all whom it may concern:

Be it known that I, CHARLES ASHTON HENRY BULLOCK, a subject of the King of Great Britain, and resident of London, England, have invented certain new and useful Improvements in Printing Presses, of which the following is a specification.

This invention relates to printing presses and has reference to printing presses adapted to be run continuously by a rotary motion.

The invention consists broadly of a machine having its type or plate when used as an offset machine stationary while inking and impression rollers rotate around the stationary type means being provided for applying and removing the sheets to be printed upon.

In order that the invention may be clearly understood and readily carried into practice the same will now be fully described with reference to the accompanying drawings which illustrate a printing press constructed in accordance with and embodying my invention, and in which—

Fig. 1 is an elevation of the press,

Fig. 2 a plan view,

Fig. 3 is a part end elevation looking in one direction, with the cover plate removed.

Fig. 4 a part end elevation looking in the opposite direction, with the cover plate or frame removed.

Figs. 5, 6 and 7 are details of the paper stripper mechanism hereinafter more fully described.

Figs. 8 and 9 are a front and side elevation of a detail hereafter to be described.

Referring to the drawings the numeral 1 designates the frame of the machine or press, 2 and 2^a shafts carrying chain wheels 3 connected by endless chains 4 motion being imparted thereto by a handle 5. Mounted upon the chains 4 are shafts 6 carrying inking rollers 7, and a shaft 8 carrying pressure roller 9. Pillars or supports 10 extend across the press and support a base plate 11 to which are secured brackets 12 adapted to rest on the supports 10. A toothed or ratchet disc 13 is rotatably mounted, preferably on ball or roller bearings, on the base plate 11 and is actuated by a pawl and ratchet movement. The underside of this disc 13 is an inking or ink distributing plate or disc 14, a circular opening being made in the base plate so that the ink may be distributed evenly on the rollers 7 when the

same move under the ink distributing plate 14. The type is set up in a chase 15 said chase resting upon the supports 10 between guide strips 16 thus retaining the chase in position when printing. A sump or duct 17 is suitably supported on lower guide rails 18 adapted to supply ink to a feed roller 19. The three ink rollers 7, 7 and 19 are journaled in plates or brackets 20 mounted on or carried by the shafts 6, and it will be observed that a slot 21 is provided to allow for the difference in pitch between the centre of the two rollers 7 due to the curvature of the chain when the rollers are passing around the end portions. A similar slot 21^a is provided for the shaft of the roller 19 so that the said roller may fall into engagement with the sump roller 22 which supplies ink from the sump and distributes it over the rollers 7.

The operation of the machine is as follows:—

Assuming the parts are in the position shown in Figs. 1 and 2 the spring paper clip 23 has just been opened up for the reception of the paper. This is effected by a lever 24 suitably mounted in guides 25 (see Fig. 4) the said lever receiving a reciprocatory motion from a cam or eccentric 26 rigidly mounted upon a toothed wheel 27 gearing with a pinion 28 on the shaft 2^a on which handle 5 is secured for effecting rotary motion of the chain wheels 3 and imparting motion to the chains 4. As the lever 24 moves forward its end 30 engages a lip 31 on the upper member of the spring clip 23. Two springs are mounted on the shaft or spindle of the paper clip, a main spring 32 for ensuring return of the whole clip to its normal position after actuation and an auxiliary lighter spring 33. It will be understood that on actuation of the lip 31 by engagement therewith of the end of lever 24, the spring clip 23 is raised slightly and at the same time opened out as shown in Figure 1 for the reception of the paper which is placed in position with its edge up against the lip 23^a. As the pressure roller 9 moves forward it engages the lower member of the clip closes the same and thereby effects a grip upon the paper. The pressure roller continuing turns or rotates the clip carrying the sheet of paper brought forward from the feeding platform so that it lays the paper with the surface to be printed flat upon the type etc. from which it is to re-

ceive the impression the type having been previously inked by the passing over of the ink rollers. Meantime the cam or projection 34 on the clip engages the end of a 5 spring controlled latch or lever 35 and retains one member of the clip in the position shown in Fig. 3, the other member of the clip flying open as shown by the action of the auxiliary spring 33. A stripper mecha- 10 nism 38 pivotally mounted on a shaft 40 secured to the chains 4 now comes into operation to pick up the paper and present it to friction guide pulleys 37 for subsequent delivery into a receiving receptacle or box 36. 15 The action and operation of the stripper will be best described by reference to Figs. 5, 6 and 7. When moving over the paper clip 23 the stripper passes through an opening 23^b cut in one member of said clip and the spring 20 controlled lips 39 of the stripper seize the edge of the paper. A tilting lever 41 mounted upon the shaft 40 engages a fixed projection 42 on the guide rail 43 thus rocking the stripper to the position shown in Fig. 6. 25 During this upward movement of the stripper 38 a link 44 mounted at 45 to a connecting bar 46, rocks the spring lips 39 about the centre 47 thus carrying the paper round to the position shown in dotted broken line 30 (Fig. 6). The paper is thus stripped from the type and carried along to the friction pulleys 37 which relieve it from the stripper and deposit it into the tray or box 36. Motion is imparted to the friction rollers 37 by 35 means of a wheel 48 meshing with the chain 4, a toothed pinion 49 secured on the same shaft as the wheel 48 meshes with a toothed wheel 50 and transmits motion to a pinion 51 on a shaft 52 carrying the friction rollers 40 37. The shaft 52 revolves in bearings 53 fixed to the frame of the machine or mounted as at 54 to the frame of the machine. The lower shaft 56 and friction pulleys 37 are journaled in brackets 57 secured to exten- 45 sions 58 on the machine frame. From the position shown in Figs. 1 and 2 the inking rollers 7 pass around with the chain to the underside, whilst the feed roller 19 in passing the sump roller 22 picks up a supply of 50 ink and distributes it upon the ink rollers 7, a more even distribution being maintained by contact of the said rollers 7 with the distributing plate 14. Bowls or rollers 59 on the inking roller shafts run on the lower 55 guide rails 18 so as to maintain contact of the rollers 7 with the plate 14. Similar bowls or rollers 61 are provided on the pressure roller shaft 8 and as the pressure roller 60 9 travels over the chase containing the type pressure is exerted upon the paper to effect an impression since the bowls or rollers 61 run under upper guide rails 62. This pressure can be regulated or adjusted by means of screws 63 and springs 64 to exert more or 65 less pressure on the bowls 61 and pressure

roller as desired. As the pressure roller moves over the type it comes into contact with a bell crank lever 65 pivotally mounted to the lever or latch 35, release of the paper clip 23 being thus effected both members which now spring back to their normal position this being effected by the main spring 32 which is of greater strength than the spring 33.

The pressure roller completes its travel over the paper and passes round the end and underneath the frame 66, the bowls or rollers 61 are so disposed that they do not engage the lower guide rails 18 and the roller therefore sags on the chain and thereby clears the inking plate 14 when passing thereunder. At the same time as the pressure roller is passing underneath, that is when the inking rollers are passing over the type, a ratchet pawl 67 is actuated to rotate the ratchet disc or plate 13 and consequently the ink distributing plate 14 through a portion of a revolution thus ensuring that even distribution of the ink upon the inking rollers is effected. This operation will be clearly understood upon reference to Fig. 4. A connecting bar 68 is mounted upon the toothed wheel 27 said lever being connected at its other end 69 to a sliding shoe or block 70 with guide plate 70^a sliding and reciprocating in the slot 71 provided in the frame 66. Pivotally mounted upon an extension 70^a of the block 70 is the spring actuated pawl 67. It will thus be seen that a reciprocating motion is imparted to the block 70 and pawl 67 thereby effecting actuation of the ratchet disc or plate 13.

To summarize briefly the operation of the press the handle 5 is rotated continuously and the inking rollers 7 travel over the type and ink the same. When they reach the forward end of the stroke the pressure roller 9 commences to turn over the clip holding the paper and subsequently rolls over the paper causing the impression to be taken from the inked type below.

The stripper 38 then takes hold of the edge of the paper strips it from the type and presents it to the friction discs 37 for subsequent delivery to the tray or box 36. The inking rollers 7 receive a supply of ink when passing the sump roller 22 and even distribution is effected when making the return stroke and passing under the inking plate 14.

It will be observed that the paper clip 23 is clear of the path of the inking rollers when the same are about to commence their forward inking stroke, but the clip 23 is arranged to be in the path of the pressure roller 9 when the same is about to commence its forward pressure stroke.

The spring clip comprises two jaws mounted upon a common hinge pin and held open by a spring. A further spring operates to maintain the clip in a lowered posi-

tion clear of the path of both the pressure and inking rollers.

- When the inking roller has passed, the rod 24 is moved by the cam 26 into contact with 5 a projection on the upper jaw. As a consequence the clip is turned to the position shown in Figs. 1 and 4 ready for the paper. The clip is now in the path of the pressure roller which contacts with the lower jaw 10 serving to close the same against the upper jaw and turn the whole clip over. The continued movement of the pressure roller serves to lay the paper on the surface of the platen.
- 15 The stripper 38 is arranged to assume its normal position (see Fig. 5) before the commencement of its forward stroke by reason of the tilting lever 41 running off its guide rail at 72.

- 20 One means for automatically stopping the rotary movement when the paper clip is in a position to receive a sheet of paper is illustrated in Figs. 8 and 9. These means necessitate the crank handle 5 being mounted 25 upon a separate spindle 73, the drive to the main spindle 74 being through interposed gearing 75 and 76. The stopping means comprise a stop 77 carried by the end of a spring controlled trigger 78 slidably mounted upon the crank handle 5 which stop is adapted to periodically co-act with a further stop 79 carried by the free end of a pivoted arm 80. This arm is normally held in a position where its stop is clear of 35 the trigger stop 77 by resting upon the peripheral flange of a wheel 81. This flange is provided with a flat 82 which permits the arm 80 to drop to a position where its stop resides in the path of the trigger stop 77.
- 40 In this position the paper clip is ready to receive a sheet of paper. To permit the handle 5 to be again rotated when the paper is in position the trigger 78 is depressed so as to lower the stop 77 out of the path of the 45 other stop 79.

What I claim and desire to secure by Letters Patent is:—

1. A travelling press comprising a stationary platen, an endless carrier, inking and 50 impression rollers attached to said endless carrier means for moving said endless carrier so as to cause said inking and impression rollers to travel over and around said stationary platen means for inking said inking rollers at a point in their travel means for distributing the ink so applied evenly over said inking rollers, pivoted clips adapted to receive a sheet of paper and by the action of the impression roller to grip the same 55 and be turned so as to lay the sheet upon the surface of the platen further clips carried by and moving with the endless carrier adapted to engage the rear edge of the printed sheet on the platen, means for automati-

cally lifting said clips about a pivotal point 65 when the same are engaging the paper so as to pull the rear edge of the sheet upwards and forwards to peel the sheet from the platen and means for ejecting the sheet from the machine when peeled comprising pairs of 70 friction guide pulleys between which the normally rear edge of the peeled sheet is presented by the said clips.

2. A travelling press comprising inking rollers for inking the type, pressure roller 75 for effecting the necessary impression upon the paper, said rollers being mounted upon chains carried by wheels to which a rotary motion is imparted, whilst the chase containing the type rests upon a flat stationary 80 base, a sump or duct for supplying ink to the inking rollers, and means for effecting even distribution of the ink upon said rollers prior to the inking of the type, a spring controlled paper clip automatically opened and 85 closed at the desired moment for the insertion of the paper and effecting the necessary grip so that the paper may be automatically taken from the feeding platform and laid upon the type by means of the clip actuated by the pressure roller, and for automatically permitting the spring clip to open whereby a stripper device is brought into operation for the purpose of stripping the printed 90 sheet from the type and presenting it to distributing rollers for subsequent removal 95 from the press.

3. A travelling press comprising a stationary platen, an endless carrier, inking and 100 impression rollers attached to said endless carrier means for moving said endless carrier so as to cause said inking and impression rollers to travel over and around said stationary platen means for inking said inking rollers at a point in their travel means for distributing the ink so applied evenly over said inking rollers, means for automatically applying a sheet of paper to the surface of the stationary platen and means for automatically stripping the sheet of paper 105 therefrom when printed, and means for automatically stopping the movement of the endless carrier when the machine is in a position to receive a sheet of paper.

4. A travelling press as in claim 3 including 110 a pair of stops one of which is carried by a spring controlled trigger mounted upon the operating crank handle of the machine whilst the other is carried by a pivoted arm which is normally supported clear of the other stop and means for lowering said pivoted arm to cause the stops to co-act and stop the machine when a paper clip provided 115 is in a position to receive a sheet of paper substantially as specified.

In witness whereof I affix my signature.

CHARLES ASHTON HENRY BULLOCK.
